(Cl. D21—6)

To all whom it may concern:

Be it known that I, Hans K. Lorentzen, a citizen of the United States and a resident of Montclair, in the county of Essex and State of New Jersey, have invented a new, original, and ornamental Design for an End Cap for a Venetian Blind Bottom Bar, of which the following is a specification, reference being had to the accompanying drawing, forming part thereof.

Fig. 1 is an inner end perspective view of an end cap for a Venetian blind bottom bar, showing my new design.

Fig. 2 is an outer end perspective view thereof.

I claim:

The ornamental design for an end cap for a Venetian blind bottom bar, substantially as shown.
